FILLING STATION

Joseph M. Tajan, 3647 Griggs Road, Houston, Tex.

Filed Feb. 27, 1959, Ser. No. 54,774

Term of patent 14 years

(Cl. D13—1)

Fig. 1 is a front perspective view of a filling station showing my new design; and

Fig. 2 is a fragmentary perspective view of the rear of the lights shown in Fig. 1.

The opposite side and the rear view of the filling station, not shown, are substantially like the respective side and front shown in Fig. 1.

I claim:

The ornamental design for a filling station, as shown and described.
